US00D966253S

(12) **United States Design Patent** (10) **Patent No.:** **US D966,253 S**
Wu (45) **Date of Patent:** **** Oct. 11, 2022**

(54) **HOLDER**

(71) Applicant: **Anker Innovations Technology Co., Ltd.**, Changsha (CN)

(72) Inventor: **Xiangpeng Wu**, Shenzhen (CN)

(73) Assignee: **Anker Innovations Technology Co., Ltd.**, Changsha (CN)

(**) Term: **15 Years**

(21) Appl. No.: **29/817,298**

(22) Filed: **Nov. 30, 2021**

(30) **Foreign Application Priority Data**

Jun. 18, 2021 (CN) 202130377840.0

(51) **LOC (13) Cl.** **14-06**

(52) **U.S. Cl.**

(57) **CLAIM**

The ornamental design for a holder, as shown and described.

DESCRIPTION

FIG. 1 is a front top perspective view of a holder showing an inner ring in an extended position;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the holder of FIGS. 1-8 with the inner ring shown in a retracted position; and,

FIG. 10 is a front view thereof.

The broken lines depicting the remainder of the holder form no part of the claimed design.

1 Claim, 10 Drawing Sheets
